United States Patent Office

Des. 208,782
Patented Oct. 3, 1967

208,782

MENU ITEM TOTALIZER OR SIMILAR ARTICLE

Leo F. Lynk, Evanston, Ill., assignor to Counting Systems,
Inc., Evanston, Ill., a corporation of Illinois

Filed Nov. 22, 1965, Ser. No. 88,174

Term of patent 14 years

(Cl. D26—5)

— 2 —

— 1 —

FIG. 1 is a perspective view of a menu item totalizer or similar article embodying my new design, showing the front and right side thereof;

FIG. 2 is an enlarged front elevational view thereof;

FIG. 3 is a top plan view thereof; and

FIG. 4 is a left side elevational view thereof.

The bottom and rear of the counting mechanism are plain and unornamented.

I claim:

The ornamental design for a menu item totalizer or similar article, substantially as shown and described.
